(57) **CLAIM**

The ornamental design for a wound dressing, as shown and described.

DESCRIPTION

The present application is a continuation of U.S. application Ser. No. 14/418,098, filed Jan. 30, 2015, entitled “Wound Dressing and Method of Treatment”, the entireties of which are hereby incorporated by reference.

FIG. 1 is a top view of an ornamental design of a wound dressing.

FIG. 2 is a bottom view of the wound dressing of FIG. 1.

FIG. 3 is a left view of the wound dressing of FIG. 1.

FIG. 4 is a right view of the wound dressing of FIG. 1; and, FIG. 5 is a side view of the wound dressing of FIG. 1.

The broken lines illustrate portions of the wound dressing which form no part of the claimed design.

1 Claim, 4 Drawing Sheets
